UNITED STATES PATENT OFFICE.

JAMES HENRY THOMPSON, OF HOLLIDAYS COVE, WEST VIRGINIA.

ELECTRON-DISCHARGE DEVICE.

Application filed March 18, 1925. Serial No. 16,414.

This invention relates to an electron discharge device in the nature of an electron tube or bulb of the character commonly employed for various purposes, such as detecting, transmitting and amplifying electric signals; particularly in the art of wireless telegraphy and telephony.

The device of the present invention has features in common with the construction illustrated in my copending application, Serial Number 750,340, filed Nov. 17, 1924. However the parts are arranged in a different relation and in such manner as to insure economy in construction, readiness of 15 pair and maximum efficiency in operation. Another object of constructing the device as illustrated in this application, is to remove obstruction from the path of the electron and to eliminate eddy currents in the electron stream from the cathode to anode.

A further object of the invention is to reduce self-capacity in the seals to a minimum. In the construction herein shown and described, the electrode and anode conductors are widely separated.

Further objects and advantages of the invention will be set forth in the detailed description which follows:

In the accompanying drawing Fig. 1 is a side elevation constructed in accordance with the invention, with parts broken away.

Fig. 2 is a plan view thereof.

Fig. 3 is a fragmentary perspective view, and,

Fig. 4 is an underside plan view of the base of the bulb illustrating the relation of the several terminals.

Like numerals designate corresponding parts in all of the figures of the drawing.

Referring to the drawing, 5 designates the bulb and 6 the base or stem of the bulb, these parts being of well known design. The shape of the bulb makes no difference and I contemplate employing a bulb of any suitable size or shape. Sealed into the stem of the bulb are two upstanding filament supporting posts 7 and 8. Those portions of the posts which lie within the bulb 5, are of concavo-convex form in horizontal section, and have their concaved faces disposed outwardly. Each post carries four pointed ears 7^a, 7^b, 7^c, and 7^d, respectively. The upper pairs of ears are spaced from the lower pairs of ears by the relatively deep notches 7^e and 8^e, the presence of which insures ample clearance for the controlling electrode

or grid which is bifurcated to form horizontal branches leading from grid conductor 9, said branches being indicated at 9^a and 9^b, and being united at their other ends to the grid anchor 10. The ears 7^a, 7^b, 7^c, and 7^d, carry binding screws 12 which constitute the means by which the cathode constituting filaments 13, are attached to the filament supporting posts 7 and 8. These screws are preferably provided with slots 12^a upon their inner ends so that they may be turned from the inner or concave faces of the posts. This arrangement permits the approach of a screw-driver from such an angle as to facilitate the manipulation of the screws without danger of damage to adjacent parts. However it is to be understood that the heads of the screws may be slotted in the usual way so that they may be manipulated from either side, and I have so indicated them. Plates 14 and 15 are supported on posts 16 and 17, sealed in the base 6, and said plates are preferably tied together at their upper portions by a strap or bar 18. In Fig. 4 I have illustrated the usual four contact studs, two of which are marked with the letter F (indicating "filament"), one with the letter G (indicating "grid"), and one with the letter P (indicating "plate"). The studs marked F are in electrical communication through conductors indicated at 20 and 21, with the lower ends of the posts 7 and 8. The stud marked G is connected to the grid conductor 9, from which the branches 9^a and 9^b extend. The stud marked P is in electrical communication through a conductor indicated at 24 with one of the plate supporting posts.

I contemplate making the cathode or filament of any suitable refractory material such, for example, as tungsten. In my copending application above referred to, the anode plates are shown as being corrugated to lend rigidity to them and it is manifest that said construction may be employed in the present case, if desired.

Since the strands of the controlling electrode and strands constituting the filament, are in substantial parallelism, there is no tendency for eddy currents to be set up. All of the parts have such clearance with respect to each other that there is no obstruction whatever to the free flow of the electrons, with the result that a tube of maximum efficiency is produced.

It is to be understood that the invention

is not limited to the precise construction set forth, but that it includes within its purview whatever changes fairly come within the terms or the spirit of the appended claims.

Having described my invention what I claim is:

1. An electron discharge device of the character described comprising a pair of filament supporting posts, both in spaced relation to each other, with a pair of independent strands extending therebetween on each side thereof and in vertically spaced relation to each other and removably secured at their ends to said posts; a grid electrode extending around said posts at a level to bring it between the upper and lower strands of the pair of filaments where it lies in substantial parallelism with said filaments, and anode

plates disposed outwardly of the grid electrode and supports for said anode plates.

2. A tube of the character described comprising a supporting base, a pair of posts extending therefrom and in spaced relation to each other, said posts each having two pairs of ears, the pairs of ears on each post being vertically spaced from each other, binding screws carried by said ears, filaments extending between the binding posts in such manner as to constitute a pair of filaments at each side of said posts, a grid electrode of bifurcated form, extending along the opposite sides of each of the posts and in substantial parallelism with the filaments, and anode plates disposed outwardly of the grid electrode.

In testimony whereof I affix my signature.
JAMES HENRY THOMPSON.
